CLAIM

The ornamental design for a combined combat harness and holster, as shown and described.

DESCRIPTION

FIG. 1 is a front elevational view of a combined combat harness and holster showing my new design;

FIG. 2 is a left side elevational view thereof;

FIG. 3 is a right side elevational view thereof;

FIG. 4 is a top plan view thereof;

FIG. 5 is a perspective view of the holster which is shown separate for clarity of illustration;

FIG. 6 is a rear elevational view thereof; and

FIG. 7 is a perspective view thereof.
